UNITED STATES PATENT OFFICE.

EDWARD BLUM, JR., AND WILLIAM BLUM, OF CHICAGO, ILLINOIS.

PHOTOGRAPHIC TRANSFER.

Application filed February 14, 1924. Serial No. 692,885.

The invention relates to photographic transfers and its object is to provide an improved method of transferring prints onto glass or other plates and which, when transferred, will produce a picture with an attractive and sparkling or metallic effect.

The invention consists in the several novel features hereinafter set forth and more particularly defined by the claim at the conclusion hereof.

In the drawings: Fig. 1 is a diagrammatic sectional view on an enlarged scale of a printed strip of carbon tissue applied to a glass plate. Fig. 2 is a view similar to Fig. 1, showing the carbon tissue strip with the backing removed. Fig. 3, is a diagrammatic sectional view on an enlarged scale of the finished transfer.

In the practice of the improved method of producing photographic transfers, a sensitized strip or roll 4, generally known as "carbon tissue", and which consists of a coating or film 4 of transferable pigment containing colors sensitized with potassium bichromate and spread on and adhering to a backing of paper 4^b is first printed from the desired negative by exposing it to light in the usual manner. The print is then dipped in cold water and applied with its film side against the back of a glass plate 5 or upon the face of a metal plate and is squeegeed onto the plate. Next, it is dried for about 15 minutes under a slight pressure. Next, the print is developed by immersion of the plate with the print thereon in warm water, ranging from 95° to 110° Fahr. This developing is continued until the surface pigment has been released by dissolving it in warm water. The paper backing comes off the plate during this development. Next, the plate with the developed film thereon is thoroughly dried. When the transfer is made on a transparent plate, a coating 6 of silver or gold bronze is applied to the back of the plate. This bronze is visible through the light or transparent spots of the trans-

ferred film and gives the picture a sparkling or polished and metallic effect. When the transfer is made onto metal, the metal is given a polish or suitable finish which will give a metallic appearance or sparkling effect to the light spots in the transfer. When the transfer is made on a glass or a transparent plate, it is given a protective coating 7 of shellac and provided with a backing of cardboard to prevent the transfer from being marred or mutilated.

The transfer, when made in accordance with the foregoing method, has an attractive and sparkling metallic effect according to the character of the bronze used, resulting from the bronze on the glass plate or the polished face of the metal plate itself when a non-transparent plate is used, appearing through the light portions of the transfer.

The invention is not to be understood as restricted to the details set forth, since these may be modified within the scope of the appended claim, without departing from the spirit and scope of the invention.

Having thus described the invention, what we claim as new and desire to secure by Letters Patent, is:

That improvement in making photographic transfers which consists in first dipping a strip of undeveloped printed carbon tissue in cold water, then pressing the film side of the wetted strip against one face of a rigid transparent plate, then drying the strip, then developing the film while the strip is on the plate and removing the backing of the strip during development, then drying the developed film, then applying a bronze coating to the back side of the developed film which will appear through the plate and the light spots of the film to form a background, and then applying a protective covering to the bronze coating.

Signed at Chicago, Illinois, this 7th day of February, 1924.

EDWARD BLUM, JR.
WILLIAM BLUM.
